UNITED STATES PATENT OFFICE.

NICHOLAS DREIS, OF HASTINGS, MINNESOTA.

SCRAPER AND GRADER.

SPECIFICATION forming part of Letters Patent No. 732,621, dated June 30, 1903.

Application filed May 28, 1902. Serial No. 109,334. (No model.)

To all whom it may concern.

Be it known that I, NICHOLAS DREIS, a citizen of the United States, residing at Hastings, in the county of Dakota and State of Minnesota, have invented a new and useful Scraper and Grader, of which the following is a specification.

My invention is an improved scraper and grader adapted to be moved alternately in opposite directions when at work to fill the scraping-bowls and adapted to be used in connection with a traction-engine and to be guided in any required direction when at work; and it consists in the peculiar construction and combination of devices herein-after fully set forth and claimed.

In the accompanying drawings, Figure 1 is a top plan view of a scraper and grader constructed in accordance with my invention. Fig. 2 is a vertical longitudinal sectional view of the same. Figs. 3 and 4 are transverse sectional views of the same, taken, respectively, on the planes indicated by the lines *a a* and *b b* of Fig. 2.

In the embodiment of my invention I provide a carrying-frame 1, which is widened at its ends and contracted in width at a point midway between the ends, as at 2. The said frame may be of any suitable construction. The frame here shown comprises a pair of longitudinal bars 3, which are appropriately spaced apart, end bars 4, which are disposed transversely with reference to the bars 3 and connect the same together and the said end bars 4 being of such length that their ends will project laterally beyond the outer sides of the bars 3, intermediate cross-bars 5, which correspond in length with the end bars 4 and also connect the bars 2 together, and side bars 6, which connect the outer ends of the bars 4 together at the respective ends of the frame.

A supporting-truck 7 is disposed over the center of the frame 1. In the form of my invention here shown the said supporting-truck comprises a pair of bolsters 8 9, disposed one above the other, independent axles 10, which are pivoted between the said bolsters, near the ends thereof, by bolts 11, which also secure the bolsters under the frame, and supporting-wheels 12, which are mounted on spindles at the outer ends of the said independent axles. The latter have their inner

portions provided with segment-gears 13, which engage opposite sides of a spur-pinion 14. Said spur-pinion is near the lower end of a vertical shaft 15, which has its bearings in the bolsters 8 9 and is provided at its upper end with a tiller or hand-wheel 16. It will be understood that by turning the shaft 15 the independent axles 10 will be turned on their pivots 11 to dispose the wheels 12 at any desired angle or relation to the frame 1, and yet preserve the parallel relation of the said wheels 12, and hence the machine may be guided in any direction. In operation one end of the frame 1 will be coupled to a suitable steam or other form of traction-engine. The same will serve to support the frame 1 in a horizontal or approximately horizontal position and will enable the machine to be moved both forward and back. I show a tongue 17 at one end of the frame 1. This tongue enables the machine to be coupled to a traction-engine, as hereinbefore indicated, and, if preferred, the frame may be constructed with a tongue at each end thereof, so that either end of the frame may be coupled to a traction-engine.

I do not desire to limit myself to the use of my scraper and grader in connection with a traction-engine, as the same may be drawn by other suitable means; but in practice I find a traction-engine most efficient in alternately moving the scraper and grader forwardly and rearwardly, which is required in the most economical and efficient operation thereof.

Scraping-bowls of any suitable construction are carried at the respective ends of the frame 1, and the said scraping-bowls face in opposite directions toward the respective ends of the frame. In the form of my invention here shown a gang of scraping-bowls 18 is carried at each end of the frame, there being three of the scraping-bowls in each gang. I will have it understood, however, that any desired number of scraping-bowls may be carried by the frame, and I do not limit myself in this particular. Within the scope of my invention any suitable means may be employed for raising, lowering, and tilting or dumping the scraping-bowls, and I do not limit myself in this particular. In the form of my invention here shown each gang of scraping-bowls is supported by a crank-shaft 19, which has

bearings in the frame 1, the said scraping-bowls being each provided with hangers 20, which are pivotally connected at 20^b with bifurcated operating-levers 21, mounted securely upon the cranks of the shaft. The rear ends of the bowls are provided with beveled lugs 25, adapted to be engaged by hooks 26, pivotally connected with the levers 21. Supporting-hooks 22 are also pivotally connected with the frame to engage studs 27 upon the sides of the scraping-bowls. The ends of the frame are provided with curved arms 28, terminating in hooks 29, which are adapted to engage the beveled lugs 25 of the scraping-bowls when the latter are tilted, as shown at the right-hand end of Fig. 2 of the drawings. The upper ends of the hook members 22 are connected, by means of link-rods 30, with operating-levers 23, by means of which they may be conveniently manipulated. The operation of this part of the device will be readily understood by reference to Fig. 2. By depressing the levers 21 the forward ends of the bowls may be raised until the studs 27 engage the hooks 22 where they are supported. By continuing the downward movement of the levers the hooks 26 will engage the beveled lugs 25, thus enabling the rear parts of the bowls to be raised clear of the ground, and in this manner the bowls may remain suspended while the load is being carried. When it is desired to tilt the bowls for the purpose of discharging the load, the ends of the levers are first depressed until by manipulating the levers 23 the hooks 22 may be disengaged from the studs 27. The ends of the levers 21 are then raised, the hooks 26 being still in engagement with the beveled lugs 25 until the bowls are completely tilted to the position shown at the right-hand end of Fig. 2. In this position they may be held by the hooks 29 engaging the beveled lugs 25, the latter being of a width sufficient to admit of such engagement.

In the operation of my improved scraper and grader the same is first run forwardly, the front gang of scraping-bowls having been disposed in operative position, thereby causing the front gang of scraping-bowls to be-

come filled with earth. The machine is then stopped and the front gang of bowls either discharged of their contents or elevated, so that they may carry their contents to another point. The rear gang of scraping-bowls having been lowered and disposed in operative position, the machine is then backed, thereby causing the said rear gang of scraping-bowls to be filled with earth, as will be understood, and they may be either at once discharged of their contents, if the conditions permit, or they may be elevated and disposed to carry their contents to another point before discharging the same. It will be understood that while the scraper and grader is being thus moved alternately in reverse directions the same may be appropriately guided by the means hereinbefore described.

Having thus described my invention, I claim—

1. A scraper and grader comprising a frame, having oppositely-faced scraping elements at its respective ends, a pair of bolsters disposed one above the other intermediate the ends of the frame, stub-axles mounted pivotally between said bolsters and having rack-segments at their inner ends, a pinion engaging said rack-segments a shaft carrying said pinion and a tiller-wheel, and supporting-wheels upon the stub-axles.

2. A scraper and grader comprising a frame having oppositely-faced scraping elements at its respective ends, and a supporting-truck disposed intermediate the ends of the frame, substantially as described.

3. A scraper and grader comprising a frame having oppositely-faced scraping elements at its respective ends, a pivoted supporting-truck disposed intermediate the ends of the frame, and means to turn the said truck and thereby guide the scraper and grader, substantially as described.

In testimony that I claim the foregoing as my own I have hereto affixed my signature in the presence of two witnesses.

NICHOLAS DREIS.
